UNITED STATES PATENT OFFICE.

WALTER H. SMITH, OF NILES, OHIO, ASSIGNOR TO THE HARRIS AUTOMATIC PRESS COMPANY, OF NILES, OHIO, A CORPORATION OF OHIO.

DAMPENING MECHANISM FOR PRINTING-PRESSES.

1,029,239.

Specification of Letters Patent. Patented June 11, 1912.

Application filed April 4, 1910. Serial No. 553,270.

To all whom it may concern:

Be it known that I, WALTER H. SMITH, of Niles, in the county of Trumbull and State of Ohio, have invented certain new and useful Improvements in Dampening Mechanism for Printing-Presses; and I do hereby declare the following to be a full, clear, and exact description of the invention, such as will enable others skilled in the art to which it appertains to make and use the same.

The primary object of this invention is to provide means for simultaneously controlling the transfer rolls of a lithographic or other printing press so that they may be moved simultaneously into and out of position, and also be capable of being moved out of and returned automatically to normal position independently of and without affecting the controlling means.

20 A further object is to provide means whereby the transfer rolls may be adjusted while the machine is in motion, and also be readily movable from their supports and capable of being replaced without adjustment 25 relatively to the press cylinder with which they coöperate.

The invention will be hereinafter fully set forth and particularly pointed out in the claims.

30 In the accompanying drawings, Figure 1 is a side view, a portion of a printing press cylinder being shown. Fig. 2 is a similar view with the side frame of the dampening mechanism removed. Fig. 3 is a plan view 35 of the mechanism at one side of the press. Fig. 4 is a view in perspective. Fig. 5 is a detail.

Referring to the drawings, 1 designates a frame which is shown as held by capped 40 screws 2 to the main press frame 3, a portion only of which is shown. This frame 1 supports a water or other fluid-containing pan 4 wherein runs a roll 5 whose shaft is mounted in fixed bearings. As customary, 45 a doctor roll 6 is intended to intermittently engage roll 5 and transfer moisture therefrom to a third roll, and said doctor roll, for this reason, is shown as journaled in arms 7 of a shaft 8 which may be oscillated 50 by any suitable means.

The third roll constitutes the moisture distributing medium; it is shown at 9, and its shaft is journaled in a sleeve 10 which is fixedly held in the side of the frame by a set 55 screw 12. Any suitable means may be em-

ployed for rotating the distributing roll provided such rotation be at the face speed of the plate-carrying cylinder. According to the means shown, a gear wheel 13 meshes with a gear wheel 14 of the plate-carrying cylinder 15, and also with the gear wheel 16 on the shaft of roll 9, causing the latter to revolve at the face speed of the cylinder. This gear wheel 13 is mounted on a stud of an arm 17 of sleeve 10. (See Fig. 3.)

18 and 19 designate upper and lower dampening rolls for transferring moisture from the main distributing roll 9 to the plate of cylinder 15. It is the purpose of my invention to enable these rolls to be moved out of their normal positions when engaged by the plate or raised portion of a cylinder, and automatically return to their normal positions when free of such plate or raised portion, and likewise to enable the 75 rolls to be adjusted while the machine is in motion, as well as be capable of being simultaneously thrown out of and into engagement with the plate cylinder by means which will not interfere with the independent 80 movement of each roll and its support. The means shown for accomplishing these objects may be varied, but that shown is preferred. The two rolls are carried by upper and 85 lower arms 20 and 21, which are loosely supported by sleeve 10, said arms at their free ends having circular openings to accommodate eccentric bearings 22 having openings for the journals of the roll, said latter openings being off center. The outer 90 ends of these bearings are milled to enable them to be easily turned to adjust the positions of the rolls in their carrying arms according to the degree of contact it is desired to maintain between such rolls and the 95 distributing roll. These bearings are held by set screws 23, by loosening which latter, the bearings may be withdrawn from the supporting arms by a lengthwise movement, whereupon the journals of the rolls may be 100 passed outwardly through slots in the ends of the arms. The bearings have lugs 23^a for engaging adjustable stops 23^b of the arms, said stops serving as guides in restoring the rolls and bearings.

105 For manually shifting the two dampening rolls simultaneously, that is to say, for throwing them into or out of engagement with the plate-carrying cylinder, I provide 110 upper and lower crossed levers 24 and 25

which are shown in the form of hubs loose on the fixed sleeve 10 and having long and short arms. With the short arms, (which are really lugs) are designed to engage adjusting screws 28 mounted in projections of the upper and lower arms 20 and 21. The upper lever 24 controls the lower roll, while the lower lever 25 controls the upper roll. By forcing or moving apart the long arms these levers will effect the simultaneous disengagement of the rolls from the plate-cylinder and swing them circumferentially around the distributing roll 9 with which they are preferably designed to remain in contact. By adjusting the screws 28 the rolls may be adjusted toward or away from the plate cylinder to regulate the degree of contact therewith, and this adjustment may be effected while the press is in operation.

The means for actuating the levers to effect the shifting of the dampening rolls may be varied, but the particular means shown comprises a cam 30 which lies between the long arms of the levers and is carried by a shaft 31 having a handle 32. By turning this shaft so as to present the narrow sides of the cam to the long arms the latter will be moved apart (see Fig. 2) their hubs turning on the fixed sleeve 10. In this way the rolls will be removed from the cylinder since the short arms of the levers transmit the motion of the latter to the two roll-carrying arms. When the flat sides of the cam are presented to the long arms of the levers the rolls will be moved into position to engage the plate, the upper roll and its arm moving downward by gravity, although it may be accelerated by spring pressure. To effect the proper positioning of the lower roll I preferably employ a coiled spring 33 which acts on a rod 34 pivoted to the outer end of the arm carrying the lower roll. This rod is shown as passed through a relatively fixed part 35 against which the lower end of the spring bears. By this means the lower dampening roll will have the same degree of contact with the plate cylinder as the upper roll. The set screw 28 of the upper roll-carrying arm bears down upon the short arm of the lower lever 25, while the set screw of the lower roll-carrying arm bears up against the short arm of the upper lever 24, being so held by spring 33. In consequence, both rolls and their supports may be swung away from normal position when the rolls are engaged by the plate or raised portion of a cylinder, and upon being free from the latter return to position automatically. This movement of the rolls and their supports has no effect upon, and is in no way prevented by, the manually-operable means by which both rolls are simultaneously moved into and out of position.

When it is desired to entirely remove the dampening rolls 18 and 19 from their carrying arms, such arms are swung on their pivot bearings, the lower arm assuming the position indicated in dotted lines, Fig. 2, 70 and is so held by spring 33. The slots in the bearing ends of these arms allow the shafts of the rolls to be passed therethrough after the eccentric bearings are removed.

It will be understood that I have shown but one side of a press, and that the mechanism is substantially duplicated at the other side, with this exception, however, that the gear wheel 13 and its supporting arm are required on only one side. It will also be understood that my invention is not confined to the details of construction and arrangement herein described and shown in the drawings, but such means I believe to be best adapted for attaining the desired 85 ends.

The advantages of my invention will be readily understood. It will be seen that the upper and lower dampening rolls may, with facility, be adjusted while the press is 90 in operation, both in relation to the plate-carrying cylinder and to the moisture-distributing roll, and that by means of a single element they may be permitted to simultaneously engage with, or be disengaged 95 from, the press cylinder, and that independently of such means each roll is capable of being moved away from and automatically returned to its normal position. There is no positive connection between the 100 rolls or their supporting arms and the shifting means.

I claim as my invention:—

1. In combination with a press cylinder, a distributing roll, upper and lower transfer rolls for engaging said distributing roll and said plate cylinder, manually-operable means located between the two rolls for moving them in opposite directions out of engagement with the press cylinder, each roll being capable of being moved out of normal position by such cylinder without interference by such manually-operable means, and means acting on the lower roll for returning it to its normal position when so moved, 115 the upper roll being returned by gravity.

2. In combination with a press cylinder, a distributing roll, upper and lower transfer rolls for engaging said distributing roll and cylinder, arms supporting said transfer rolls pivoted concentrically to the axis of said distributing roll, upper and lower levers interposed between said arms, and means for operating said levers for moving said arms and rolls in opposite directions, said arms and rolls being capable of being moved out of, and returned to, their normal positions independent of said levers.

3. In combination with a press cylinder, a distributing roll, upper and lower transfer 130

- rolls for engaging said distributing roll and cylinder, arms supporting said transfer rolls pivoted concentrically to the axis of said distributing roll, set screws carried by said arms, levers interposed between said arms and with which said set screws engage, and means for operating said levers to move said arms and rolls in opposite directions, said rolls and their arms being capable of 10 being moved independently of said levers by the press cylinder.
4. In combination, a distributing roll, arms loosely supported concentrically to the axis of said roll, transfer rolls carried by 15 said arms, each arm having an adjusting screw, levers fulcrumed concentrically to the axis of said distributing roll and with which said adjusting screws are designed to engage, and means connecting said levers for 20 shifting the transfer rolls.
5. In combination, a distributing roll, a fixed sleeve, arms loosely supported by said sleeve, transfer rolls carried by said arms, each arm having an adjusting screw, levers 25 fulcrumed on said sleeve and with which said adjusting screws are designed to engage, and means engaging said levers for shifting the transfer rolls.
6. In combination, a distributing roll, a 30 fixed sleeve in line with the axis of said roll, arms loosely supported by said sleeve, transfer rolls carried by said arms, each arm having an adjusting screw, levers fulcrumed on said sleeve and with which said adjusting 35 screws are designed to engage, and means engaging said levers for shifting the transfer rolls.
7. In combination, a distributing roll, a fixed sleeve in line with the axis of said roll, 40 arms loosely supported by said sleeve, transfer rolls carried by said arms, each arm having an adjusting screw, levers fulcrumed on said sleeve having short arms with which said adjusting screws engage, and means enga- 45 gaging the long arms of said levers for moving them to change the positions of the transfer rolls.
8. In combination, a distributing roll, a fixed sleeve in line with the axis of said roll,
- arms loosely supported by said sleeve, trans- 50 fer rolls carried by said arms, each arm having an adjusting screw, levers fulcrumed on said sleeve having short arms with which said adjusting screws engage, a cam located between the long arms of said levers, and 55 means for actuating said cam.
9. The combination with a distributing roll, of upper and lower arms having a common pivot concentrically to the axis of such distributing roll, transfer rolls carried by 60 said arms, crossed levers fulcrumed concentrically to the axis of said distributing roll for simultaneously moving both arms and rolls out of normal position, and permitting them to move into normal position, the upper 65 roll being so moved by gravity, and a spring acting on the lower roll for returning it to, and holding it in, normal position.
10. The combination with a main roll, of upper and lower arms having a common 70 pivot concentric to the axis of said roll, transfer rolls mounted in the outer ends of said arms, adjusting screws carried by said arms, levers having hubs mounted concentrically to said arms, said adjusting screws 75 engaging the short arms of said levers, a shaft, a cam thereon located between the long arms of said levers, and a spring acting on the lower of said arms.
11. In combination with a distributing 80 roll, upper and lower transfer rolls in contact therewith, supports for said rolls having openings and slots leading therefrom, bearings for the shafts of said rolls having eccentrically-arranged openings therefor, 85 said bearings being mounted in said openings and capable of being withdrawn therefrom to permit said shafts to be passed outwardly through said slots, and adjustable stops for regulating the positions of said 90 bearings in said supports.

In testimony whereof, I have signed this specification in the presence of two subscribing witnesses.

WALTER H. SMITH.
